Attorney

UNITED STATES PATENT OFFICE.

HERMAN T. SCHNEIDER, OF GARNER, IOWA.

CLEANING DEVICE.

1,348,748.

Specification of Letters Patent.

Patented Aug. 3, 1920.

Application filed February 13, 1920. Serial No. 358,488.

To all whom it may concern:

Be it known that I, HERMAN T. SCHNEIDER, a citizen of the United States, residing at Garner, in the county of Hancock and 5 State of Iowa, have invented certain new and useful Improvements in Cleaning Devices, of which the following is a specification, reference being had to the accompanying drawings.

10 This invention relates to certain improvements in cleaning devices and has relation more particularly to a device of this general character and especially adapted for use in connection with the radiator of a horse shoe 15 type as is generally employed in connection with hot air furnaces, and it is an object of the invention to provide a novel and improved cleaning device which may be effectively employed for the removal of ashes, 20 soot, dust, or other matter that may accumulate within the radiator.

It is also an object of the invention to provide a novel and improved device of this general character including a flexible or 25 pliable handle member provided at one end with a pair of oppositely directed and hingedly connected wings, foldable or movable one toward the other when the device is inserted within the radiator or other flue to be 30 cleaned and which wings open outwardly upon reverse movement of the device to a position whereby the same operate to effectively scrape or clean out sediment which may be collected within the radiator or flue.

35 The invention consists in the details of construction and in the combination and arrangement of the several parts of my improved device whereby certain important advantages are attained and the device rendered simpler, less expensive and otherwise 40 more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a diagrammatic view illustrating a cleaning device constructed in accordance with an embodiment of my invention;

Fig. 2 is a fragmentary view in top plan of my improved device with the wings in folded condition;

50 Fig. 3 is a fragmentary view partly in top

plan and partly in section of my improved device as herein embodied with the wings at the limit of their outward movement;

Fig. 4 is a fragmentary view in side elevation of my improved device with the wings 60 in their folded position; and

Fig. 5 is a view in front elevation of my improved device as herein disclosed with the wings at the limit of their outward movement.

65

As disclosed in the accompanying drawings, R denotes a conventional type of horse shoe radiator now generally employed in connection with hot air furnaces and which radiator is provided with the clean-out opening 1.

70 My improved device comprises an elongated flexible or pliable handle member H, preferably of spring steel, and which is provided at one end with a hand grasp G of any desired type whereby the device may be 75 readily and conveniently operated.

The opposite end portion of the handle member H is riveted or otherwise secured to a substantially rigid body or plate B. 80 The outer end portion of the body or plate B is provided with a transversely disposed sleeve or bearing 2, preferably integrally formed in said body or plate.

85 Disposed through the bearing or sleeve 2 is a pintle member 3. The opposite end portions of the pintle member 3 are disposed through the overlapping knuckles 4 carried by the inner longitudinal marginal portions of the wings W. In the present 90 embodiment of my invention, the wings W are substantially oblong in form with their longitudinal axes disposed in the same general direction as the sleeve or bearing 2. Welded or otherwise secured to the outer 95 face of the sleeve or bearing 2 and at substantially the central portion thereof is a central part of an elongated rod 5. The rod 5 is disposed substantially at right angles to the pintle member 3 and is of such 100 length as to have its opposite end portions extend slightly beyond the outer longitudinal margins of the wings W when said wings are in their full extended position and which position is determined by contact of the wings W with the opposite end 105 portions of the rod itself. The ends of the rod 5 are rounded, as at a. When it is desired to clean out a radiator of a horse shoe type, the body or plate B is forced through 110

110

the clean-out opening and into channels or flues of the radiator. As the wings are forced inwardly, they assume, due to the resistance offered by the sediment within the channel or flue, a folded position and thereby causes a minimum of disturbance, such as spreading or pushing the sediment. Upon a slight forward pull or strain, the wings W meeting with the resistance offered by the sediment within the channel or flue, open to their full width and a continued pull upon the wings, through the instrumentality of the handle member H, will bring the load to the clean-out opening for its final disposal. The flexibility or pliability of the handle member H permits the wings W to have proper travel within a flue or channel of the radiator. By having the rod 5 extend beyond the outer longitudinal margins of the wings W, the rounded ends a of said rod 5 will ride over rough sides of the channel or flue of the radiator and at the same time, assures a positioning of the device within the channel or flue to permit the wings W to assume their full open position.

In radiators of a horse shoe type, the collection of sediment therein reduces the heating efficiency of the radiator but with my improved device, the sediment collecting within the radiator may be readily removed without the necessity of causing the fire to die out. It has also been fully established in practice that my improved device thoroughly and effectively cleans the chan-

nel or flue in the radiator of this particular type.

From the foregoing description, it is thought to be obvious that a device constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

A cleaning device of the character described comprising a handle having a bearing on one end, a pair of wings, each wing having a knuckle on one side thereof, and a recess in its intermediate portion for the reception of a portion of said bearing, said knuckles being disposed in alinement with each other and the bearing, a pintle disposed through the bearing and the knuckles, and a rod secured to said bearing and extending beyond the bearing in right angular relation thereto, whereby pivotal movement of said wings in one direction is limited.

In testimony whereof I hereunto affix my signature.

HERMAN T. SCHNEIDER
